Attorney

UNITED STATES PATENT OFFICE.

MARY ESTELLE BAILEY, OF WASHINGTON, DISTRICT OF COLUMBIA.

DESIGN FOR AN ORANGE-KNIFE.

SPECIFICATION forming part of Design No. 32,328, dated March 13, 1900.

Application filed February 6, 1900. Serial No. 4,285. Term of patent 7 years.

To all whom it may concern:

Be it known that I, MARY ESTELLE BAILEY, a citizen of the United States, residing at Washington, District of Columbia, have invented a certain new and useful Design for an Orange-Knife; and I do declare the following to be a full, clear, and exact description of the invention, such as will enable others skilled in the art to which it appertains to make and use the same, reference being had to the accompanying drawings, which form a part of this specification.

This invention relates to a certain new and useful design for orange-knives.

15 My design is clearly illustrated in the accompanying drawings, which form a part of this specification, and in which—

20 Figure 1 is a perspective view of an orange-knife embodying my design, and Fig. 2 is an end view of the knife-blade.

As shown in the drawings, my design consists of a curved blade having a flattened por-

tion on its rear edge adjacent to its point and two curved flanges on opposite faces of said blade, said flanges starting from the flattened portion on the rear edge of the blade a short distance from the point of the blade and curving toward and merging into the curved cutting edge of said blade.

The handle portion of the knife is rectangular in outline and has an ornamental panel C on each of its opposite faces.

Having thus described my invention, what I claim as new, and desire to secure by Letters Patent, is—

35 The design for an orange-knife, as herein shown and described.

In testimony whereof I affix my signature in presence of two witnesses.

MARY ESTELLE BAILEY.
